UNITED STATES PATENT OFFICE.

WAYNE TANKERSLEY, OF FRANKFORT, INDIANA.

GAS MIXER.

Application filed May 20, 1921. Serial No. 471,036.

To all whom it may concern:

Be it known that I, WAYNE TANKERSLEY, a citizen of the United States, residing at Frankfort, in the county of Clinton and 5 State of Indiana, have invented a new and useful Gas Mixer, of which the following is a specification.

This invention relates to devices commonly known as gas mixers, it being the primary object of the invention to provide a 10 novel form of mixing device to be positioned within the manifold of an internal combustion engine, at a point between the carburetor and engine cylinders for breaking up 15 the particles of gas which has not been thoroughly broken up by their passage through the carburetor.

A further object of the invention is to provide a device of this character having 20 novel means for securing the same within the manifold of the engine, the securing means operating by frictional contact with the walls of the manifold.

With the foregoing and other objects in 25 view which will appear as the description proceeds, the invention resides in the combination and arrangement of parts and in the details of construction hereinafter described and claimed, it being understood 30 that changes in the precise embodiment of the invention herein disclosed, may be made within the scope of what is claimed, without departing from the spirit of the invention.

35 Referring to the drawing:—

Figure 1 is a sectional view through a manifold of an internal combustion engine, showing the invention as applied.

Figure 2 is an elevational view of the 40 device, positioned in the manifold.

Figure 3 is a front elevational view of the mixer; and

Figure 4 is a sectional view taken on line 44—4 of Figure 3.

45 Referring to the drawing in detail, the device is shown as positioned in the intake

manifold 5 of an internal combustion engine at a point adjacent to the end thereof that connects with the engine cylinder, it being understood however that the showing 50 of the drawing only includes one end of an intake manifold.

The device comprises an outer collar 7 and an inner sleeve 8, the collar 7 being provided with an inwardly extending flange 9 55 providing an abutment and seat for the baffle 10 which is formed of fine mesh material and provided with an inwardly extending circumferential flange 11 adapted to lie between the collar 7 and sleeve 8, to support 60 the baffle in proper relation with respect to the manifold in which the same is positioned.

Laterally extending fingers 12 form a part 65 of the collar 7 and these fingers are of constructions to frictionally contact with the inner surface of the intake manifold 5 to support the device therein. In view of the structure of the fingers 12, it will be seen that the device may be easily positioned 70 within a manifold, and by rotating the same in a predetermined direction, the fingers will frictionally engage the walls of the manifold to secure the device against movement. 75

What is claimed as new is:—

A mixing device comprising a collar, a sleeve positioned in the collar, a baffle formed of wire mesh material disposed within the collar and contacting with the 80 sleeve, and resilient fingers forming a part of the collar for frictionally engaging the walls of the manifold for securing the device therein.

In testimony that I claim the foregoing 85 as my own, I have hereto affixed my signature in the presence of two witnesses.

WAYNE TANKERSLEY.
